(57) **CLAIM**

The ornamental design for a detachable handle for cookware, as shown and described.

DESCRIPTION

FIG. 1 is a perspective view of the detachable handle, showing the upper face.

FIG. 2 is a bottom plan view of the detachable handle

FIG. 3 is an elevation plan view of the detachable handle, the right and left sides of the handle being mirror images.

FIG. 4 is a top plan view of the handle.

FIG. 5 is a front plan view of the handle; and,

FIG. 6 is a rear plan view of the handle.

The broken lines represent portions of the article that form no part of the claim.
